ELECTRIC-ARC FURNACE.

1,296,194.

Specification of Letters Patent.

Patented Mar. 4, 1919.

Application filed November 22, 1915. Serial No. 62,782.

To all whom it may concern:

Be it known that I, JENS LASSEN LA COUR, a subject of the King of Sweden, residing at Christiania, Norway, have invented certain new and useful Improvements in Electric-Arc Furnaces; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

The present invention relates to improvements in electric arc furnaces, and more particularly in furnaces for oxidizing air in a long stable electric arc under high pressure.

In furnaces of this kind, such as Schoenherr-furnaces, working at high pressure—twenty atmospheres or more—the variations in pressure and velocity of gas flow have an injurious influence on the working of the furnace and in order to remove this disadvantage one has resorted to air buffers connected with the gas pipes.

Buffers of this kind generally must be made of a considerable size and owing to this and to the high pressure they generally represent a very inconvenient complication of the plant, while at the same time they cause loss of heat. Owing to the high temperatures the material and particularly all connections may easily be damaged.

The object of the present invention is to provide a buffer arrangement for equalizing the shocks or sudden changes of pressure which does not present the inconveniences above referred to, and this object is attained by mounting the buffer directly on the furnace and combining it with the necessary cooling devices for the furnace gases. Simultaneously the pressure in the buffer is wholly or substantially balanced by means of an exterior pressure of gas, steam or liquid, which may be established either by means of an independent arrangement or by means of the combined buffer and cooling device, viz., by means of the gases flowing through the same.

In the latter case the buffer may form part of a steam boiler, while in the former case the space outside the buffer may communicate with a steam boiler in order to utilize the heat from the buffer.

On the drawings:

Figure 1 is an axial section through the top of a tube furnace and a buffer according to the invention mounted directly on the same.

Fig. 2 shows a modification of the arrangement according to Fig. 1.

Referring to Fig. 1 a steam boiler *b* is mounted directly on top of a tube furnace *a*, the main tube *c* in the boiler *b* forming a buffer for the said tube furnace. The gases pass through this main heating tube *c* back through ordinary heating tubes and escape at the outlet as indicated by the arrow. The pressure existing in tube *c* which is twenty atmospheres and over, is counterbalanced by means of the liquid or steam in the boiler *b*.

According to Fig. 2 the upper water cooled part *d* of the furnace *a* forms part of the water space in the boiler *b*, so that according to this arrangement the heat absorbed in the part *d* is also utilized for producing steam, circulation of the water contained in the part *d* and the boiler *b* taking place through openings *e*. In both of these figures *h* is the water inlet for the boiler, *i* the steam outlet therefrom, and *k* the conductor for the upper end of the flame tube *a*, said conductor usually being grounded.

In Fig. 1, *l* is the cooling water inlet, and *m* its exit from the water jacket surrounding the conical part *g*.

It is clear that the same system may be adapted for any kind of electric arc furnaces, and it may also be modified to comprise only certain parts of the buffers.

In case the stability of the furnace does not permit a high decrease in temperature in the buffer itself the flame tube, *e. g.*, the cooling action, must be reduced in the first part of the same or two boilers may be connected to the furnace with their flame tubes in series. The long stable arc necessitates a certain mobility of the end of the arc or foot point *f* adjacent the buffer in the conical part *g* at the end of the flame tube *a*.

By constructing the buffer arrangement with the buffer tube *c* directly in line with the flame tube of the furnace it facilitates the mobility of the end or foot point of the arc, and also equalizes the pressure differences in the reaction chamber *a*.

I claim:

1. The combination with a high pressure

electric arc furnace having a flame tube whose upper end is contracted and cooled; of a buffer mounted on said contracted end and receiving the gases from said furnace, and means heated by the gases issuing from said buffer for balancing the pressure in the same.

2. The combination with a high pressure electric arc furnace having a flame tube contracted at one end and said end water-cooled; of a buffer mounted on said contracted end in alinement with said tube and into which said contracted end discharges, and flame tubes of a tubular boiler into which said buffer discharges, said buffer operating to equalize pressures in said furnace above atmospheric pressure.

3. The combination with a high pressure electric arc furnace having a water-cooled contracted end; of a buffer tube of larger diameter forming a continuation of said end, said buffer tube discharging into tubes surrounding it, and means to maintain water around said tubes and buffer, whereby said buffer will equalize the pressures above atmospheric pressure in said furnace.

4. The combination with a high pressure electric arc furnace maintaining a high gaseous pressure within the arc chamber; of a buffer tube equalizing furnace pressures above atmospheric pressure and in substantial alinement with the furnace chamber, a water chamber surrounding said tube, the pressure within said chamber counteracting the pressure in said tube, and fire tubes passing through said chamber and receiving hot gases from said buffer tube.

5. The combination of a high pressure electric arc furnace having a conical end restricting the furnace outlet and at which the arc ends; with a buffer tube substantially in

alinement with the furnace chamber and of larger diameter than the contracted discharge end of said furnace, a water chamber surrounding said buffer tube and fire tubes in said chamber receiving gases from said buffer tube.

6. The combination with a high pressure arc furnace having a water cooling chamber at its upper end; of a buffer tube in alinement with and into which said upper end discharges, a boiler surrounding the buffer and means to permit circulation of the boiler water through said chamber.

7. The combination with a high pressure arc furnace having a water cooling-chamber at its upper end; of a buffer into which said furnace discharges, a water chamber surrounding the buffer, fire tubes in said water chamber through which the gases expanded in the buffer discharge, and means to permit the water of said boiler to enter said cooling chamber.

8. The combination with a high pressure arc furnace having a contracted end surrounded by a water chamber; of a buffer tube of larger diameter than said contracted end and forming a continuation of the outer wall of said chamber, a boiler chamber surrounding the buffer tube, fire tubes in said boiler chamber through which the buffer tube gases discharge, and means above the bottom of the boiler chamber to permit circulation of water from said boiler chamber through said water chamber.

In testimony that I claim the foregoing as my invention, I have signed my name in presence of two subscribing witnesses.

JENS LASSEN LA COUR.
